(57) **CLAIM**

The ornamental design for a display panel with graphic user interface, as shown and described.

DESCRIPTION

FIG. 1 is a front view of a display panel with graphic user interface showing our new design; and,

FIG. 2 is an enlarged view in which the portion within the dot-dash boundary of FIG. 1 is shown isolated for clarity of disclosure.

The dashed broken lines illustrate a display panel and form no part of claimed design. The dot-dash broken lines shown in FIG. 1 define the bounds of the claim, forming no part thereof, and indicate the portion of the display panel that is shown isolated and enlarged in FIG. 2.
